UNITED STATES PATENT OFFICE

WALTER B. ENGH, OF CHICAGO, ILLINOIS, ASSIGNOR TO THE MANTLE LAMP COMPANY OF AMERICA, OF CHICAGO, ILLINOIS, A CORPORATION OF ILLINOIS

MANTLE HEAD

Application filed March 10, 1931. Serial No. 521,466.

The invention relates to heads for incandescent mantles and it especially relates to inverted mantles such as are used with pressure type hydrocarbon lanterns having blue-flame burners.

The invention includes a metal head which is of such shape as to properly sustain the mantle, and also enable a flame applied to the combustible and thorium-impregnated fabric of the mantle to easily burn out that part of the fabric which is attached to the mantle head, whereby the fusing of the thorium content at the mantle head is greatly facilitated and the top of the mantle strengthened.

One embodiment of the invention comprehends a mantle head for inverted mantles of the so-called "rag" type, such as are used with hydrocarbon lanterns, the mantle head being of such form that the mantle may be supported in spaced relation to the burner head, whereby a minimum conduction of heat is permitted from the mantle head to the burner.

The invention involves other and useful details of construction, hereinafter to be disclosed.

Referring to the drawings, constituting a part of this invention,

Figure 1 shows in elevation a burner, a mantle and a mantle head embodying the invention;

Figure 2 is a sectional view taken on the line 2-2 of Figure 1;

Figure 3 is a plan view of the embodiment of the invention shown in Figure 1;

Figure 4 shows, in side elevation, the mantle head before the mantle is applied thereto;

Figure 5 shows, in elevation, the lower end of the burner to which the mantle head may be attached;

Figure 6 shows, in elevation, an upright mantle attached to its support, and a second embodiment of a mantle head embodying a modified form of the invention;

Figure 7 is a plan view of the mounted mantle shown in Figure 6;

Figure 8 is a plan view of the mantle head shown in the mantle of Figure 6; and

Figure 9 shows, in side elevation, the modified form of the mantle head before the mantle is applied thereto.

In the making of incandescent mantles, either of the inverted type shown in Figure 1 or of the upright type shown in Figure 6, one of the difficulties to be overcome is the production of a mantle having a top portion of sufficient strength and symmetry. In both the upright and the inverted mantle, the means by which the mantle is secured to the head thereof is customarily fashioned by folding over the upper edge of the impregnated fabric from which the mantle is formed, by shirring or gathering in the folded edge of the fabric by a cord. When the mantle is calcined and formed either on the burner with which it is to be used, or in the factory, it is difficult to burn out that part of the mantle fabric which is bunched together at the top of the mantle, and, as a consequence, it is difficult to produce mantle heads of the desired strength.

This invention involves a metal mantle head made of wire of any desired cross-sectional shape, that is so formed as to provide a suitable support for a mantle and, at the same time, employ a minimum amount of metal. Furthermore, it becomes possible to attach a mantle top to the groove of the mantle head, as shown in Figures 4 and 9, without folding over the upper edge of the fabric of the mantle, and, hence, as a consequence a small amount of impregnated mantle fabric is required to produce a mantle head.

The minimum amount of fabric thus used and the openness of the metal head construction, make it easy to thoroughly burn out and harden the head of a mantle produced in this manner.

One embodiment of the mantle head includes a preferably continuous bent wire, having laterally-extending spaced loops 1 and downwardly-extending and outwardly-inclined spaced loops 2, which together provide what is in effect a groove or seat 3, within which the upper edge of the impregnated mantle fabric and its retaining cord 5 may be seated. Said wire, furthermore, may be bent to form inwardly-extending loops 6 100

shown in Figure 3, and the ends thereof spot-welded. The loops, preferably three in number, may interlock with bayonet sockets 7 of the burner head 8 to thereby secure a completed mantle in operative position to the burner. These inwardly-extending loops 6 are, preferably, of such length as to leave a space 9 between the burner head and the mantle head, through which space and the spaces between the loops 1 and 2, the flame or hot products of combustion from the burner may pass, thus facilitating the burning out of the fabric of the mantle that is in contact with the metal head, as well as the fusing of the thorium content, and insuring the strengthening of the mantle. Due to the small mass of metal from which the mantle head is formed, and the spacing of said head from the burner, it is possible to heat all parts of a completed mantle to a high temperature, the thorium fabric of the mantle at the top of the mantle, when thus highly heated, becoming incandescent so that all areas thereof are rendered luminous.

The mantle head disclosed in this application is especially useful as a support for soft or rag mantles of the type commonly used for hydrocarbon lanterns where the user attaches the mantle to the head of the burner and burns out the fabric and hardens the mantle on the burner of the lantern where it is to be used. Heretofore, rag mantles have commonly been tied directly to the burner head by the user, and in such cases it is impossible to heat that part of the mantle in contact with the burner head to a sufficiently high temperature whereby the mantle may be calcined and the thorium therein contained fused and strengthened. In such cases, the fabric of the mantle at the point of contact with the burner is "soft" and the mantle is consequently easily broken away from the burner head.

This invention comprehends the making of a metal mantle head support, preferably of nickel and also preferably of wire, so that a minimum amount of nickel is used; and it also comprehends means for supporting the head of the mantle in spaced relation to the burner, so that the flame and the hot products of combustion will pass both inside and outside of the head, whereby the mantle head will be highly heated, and, because of the limited metallic or heat-conductive relation between the mantle head and the burner, this heat will be retained.

The second embodiment of the invention, shown in Figures 6, 7, 8 and 9, involves a form of the invention suitable for supporting an upright mantle which may be formed in the factory. In this embodiment, the mantle head possesses the wire loops 1 and 2 shown in Figures 1, 2, 3 and 4, but, instead of having the inwardly-extending loops 6, it is provided with a yoke 10 extending over a

mantle-supporting wire 12 that is held in sockets 13 carried by a burner cone 11 in a usual manner.

This form of the invention is of great value in such mantles, as it provides a mantle head which may be produced by automatic tools very cheaply, and affords a support for a mantle that permits of the head of the mantle being fired to a high temperature during the forming of the mantle, so that the thorium and other chemicals contained in the mantle head may be fused and a strong mantle head produced.

Having thus described my invention, what I claim is:

1. A wire mantle head including horizontal and inwardly-extending loops for spacing said mantle head from the burner to which it may be attached, said loops being disposed in substantially the same plane as the body of said mantle head.

2. A burner, including sockets disposed at the terminal part thereof, and a wire mantle head having internal loops disposed in substantially the same plane as the body of said mantle head and engaging said sockets.

3. A head for an incandescent mantle, said head having an elastic body portion containing alternating horizontal and downwardly-projecting wire loops.

4. A mantle head comprising a wire having alternating horizontal and downwardly-extending loops constituting a seat around which the top of a mantle may be secured, and having a suspension yoke at its upper end.

5. A mantle head comprising a wire having alternating horizontal and downwardly-extending loops constituting a grooved seat around which the top of a mantle may be secured.

6. A mantle head comprising a looped wire constituting a seat around which the top of a mantle may be secured and having horizontal internal means for spacing it from a burner.

7. A mantle head comprising a looped wire constituting a seat around which the top of a mantle may be secured and having horizontal internal loops for spacing it from a burner.

8. A looped mantle head combined with an impregnated tubular mantle fabric having its unfolded upper end surrounding and secured to said mantle head.

9. A mantle head having a body portion including vertically-arranged wire loops, and means attached to the upper end of said mantle head by which it may be suspended from a mantle-sustaining wire.

In testimony whereof I affix my signature.

WALTER B. ENGH.
